(57) **CLAIM**

The ornamental design for a foldable mobility vehicle, as shown and described.

DESCRIPTION

FIG. 1 is a front perspective view of a foldable mobility vehicle in a first configuration according to our new design; FIG. 2 is a rear perspective view thereof; FIG. 3 is a front elevational view thereof; FIG. 4 is a rear elevational view thereof; FIG. 5 is a right-side elevational view thereof; FIG. 6 is a left-side elevational view thereof; FIG. 7 is a top plan view thereof; FIG. 8 is a bottom plan view thereof; FIG. 9 is a front perspective view of the foldable mobility vehicle in a second configuration thereof; FIG. 10 is a rear perspective view thereof; FIG. 11 is a front elevational view thereof; FIG. 12 is a rear elevational view thereof; FIG. 13 is a right-side elevational view thereof; FIG. 14 is a left-side elevational view thereof; FIG. 15 is a top plan view thereof; FIG. 16 is a bottom plan view thereof; FIG. 17 is a front perspective view of the foldable mobility vehicle in a third configuration thereof; FIG. 18 is a rear perspective view thereof; FIG. 19 is a front elevational view thereof; FIG. 20 is a rear elevational view thereof; FIG. 21 is a right-side elevational view thereof; FIG. 22 is a left-side elevational view thereof; FIG. 23 is a top plan view thereof; and, FIG. 24 is a bottom plan view thereof.

(Continued)

Conventional shading and shadows are illustrated for purposes of highlighting the solid-rendering, but form no part of the claimed design.

1 Claim, 24 Drawing Sheets
